CLAIM

The ornamental design for a display screen or portion thereof with transitional graphical user interface, as shown and described.

DESCRIPTION

FIG. 1 is the first image in a sequence for a display screen or portion thereof with transitional graphical user interface showing our new design; and,

FIG. 2 is the second image thereof.

The broken line outer perimeter of the Figures illustrates a display screen or portion thereof and form no part of the claimed design. The remaining broken lines in the Figures illustrate portions of the graphical user interface that form no part of the claimed design.

The appearance of the transitional image sequentially transitions between the images shown in FIGS. 1-2. The process
